MOTOR RETURN MECHANISM FOR
TYPEWRITERSFrederick P. Gorin, Seattle, Wash., assignor, by
mesne assignments, to Elliott-Fisher Company,
a corporation of Delaware

Application February 11, 1926. Serial No. 87,699

14 Claims. (Cl. 197—66)

This invention relates to improvements in type-writing machines and more especially to such devices wherein the typewriter proper is adapted to move both transversely and longitudinally upon a flat platen, such for example as is involved in the well-known Elliott Fisher machine. The principal object of this invention is to provide a motor and means for causing the motor to impart either a transverse movement of the typewriter proper with respect to its platen or bed, and also simultaneous longitudinal movement; and also to provide selective means whereby either one of these movements may be imparted. I accomplish these and other objects by the peculiar arrangement and combination of the parts as will be more fully hereinafter described and explained in the following specification, shown in the accompanying drawings and finally pointed out in the appended claims.

20 In the drawings:

Fig. 1 is a plan view of the well-known Elliott Fisher typewriter bookkeeping machine with my device applied thereto.

Fig. 2 is a rear elevation thereof.

25 Fig. 3 is a side elevation with portions broken away.

Fig. 4 is an enlarged detailed view of the tripping and switch mechanism.

Fig. 5 is a similar view of the clutch mechanism.

30 Referring now more particularly to the drawings, reference numeral 1 indicates the usual legs of the typewriter stand tied together by the rods 2 and to which is secured the end bar 3, side bars 4 on which are toothed tracks 5 over 35 which run the toothed traction wheels or rollers 6 mounted upon the cross rod 7 which is revolvable within journal bearings 8, which extend upwardly from the side plates 9, and whose opposite ends are tied together by cross plate 10, thus 40 forming what is generally known as the sliding or rolling frame, which will be so referred to hereinafter. Upon the "rolling frame" is mounted the typewriter proper 11, commonly called the "head" and which will be so referred to. 12 indicates the usual spring drum from which extends the usual tape 13 having its opposite end connected to the "head" whereby the head is at all times urged in letterfeed direction controlled by its usual feeding mechanism, which includes a 45 feed rack 14 and pinion 15. 16 is the usual hand tripping lever for releasing the feeding mechanism. 17 is the usual flat writing bed or platen which has a slight vertical movement so as to allow the written sheets to be removed from the 50 grip between the bed and the strips 18. 21 are

the usual pedals which, through the connecting rod 22, causes the slight vertical movement of the bed. 23 is the usual banking stop which arrests the head when it is returned in contraletterfeed direction to its initial writing point. 24 is the usual cross bar which is adapted to receive the usual adding boxes. 25 is one of the usual ribbon spools. 26 indicates the cross tracks upon which bear the usual rollers 27 mounted upon the head so that the head may have a free 55 lateral movement with respect to the rolling frame.

The foregoing description is considered sufficient to fully identify the usual and well-known Elliott Fisher machine, in which no changes are 70 necessary whatever in order to apply my device to it except as will be now fully described and explained. 28 indicates an electrical motor secured to the typewriter stand at 29. 30 indicates the wires from the outside source of electrical 75 energy such as the usual municipal power plant. 30' indicates conducting wires from the motor to points 31 where they are secured to the side bars 4, being insulated therefrom. 32 is a plate hinged to the side bars 4 at 33, and which is 80 maintained in its position as seen in Fig. 4, by contact with the extension 34 of the usual hand-tripping lever 16 and the extension of a similar lever 35 which is pivotally mounted upon an extension 36 from one of the bars 4. The 85 usual hand tripping lever is operated to cause the head to move towards the operator upon its rolling frame in the usual line spacing operation, and of course when this operation occurs the head cannot move upon its rolling frame away from 90 the operator. The lever 35 however being mounted upon the fixed frame work or stand of the typewriter, instead of upon the head, can be operated independently of the usual hand tripping lever 16 and vice versa. The operation of either of the 95 levers will cause the plate 32 to move about its pivot 33 until it contacts with the two wires at 31 and thus closes the electrical circuit. 37 is a spool which is normally free to revolve upon the shaft of the motor 28, when the circuit is open. 100 When the circuit is closed, however, and the motor shaft caused to revolve, a collar 38 which is secured to the shaft will revolve with it and cause the free ends of arms 39 pivoted to a collar at 40 to move into their dotted positions 105 as seen in Fig. 5 which shows a contact of the arms with the side walls 41, of slots 42 in the spool. A spring 43 normally holds the arms out of contact with the walls of the slots. 44 is a 110 flexible connection such as a leather belt, prefer-

ably circular in cross section, having one of its ends secured to the spool and its opposite end secured to one end of a spring 45, whose opposite end is secured to the head 11. The belt passes through a smooth tube 46, secured to a bracket 47 which is rigidly mounted upon the casting 8. The usual feed rack 14 is mutilated as at 49 so that when the head be returned to its initial writing point, the usual feed pinion 15 will be out of mesh with the rack until the head be returned in the opposite direction by its usual motor spring, when the feeding mechanism will again be reconnected and the head arrested at the exact predetermined writing point. During the travel of the head toward its initial writing point, and a short distance before it reaches it, the head contacts with a plunger 50 which is slideable within a dash pot 51, secured, by means of a bracket 52, to the rolling frame, so that the impact incident to the arrest of the head is fully cushioned; but notwithstanding the vibration of the head caused by such cushioning, the head will be at all times finally arrested exactly at the initial writing point, because, while the feed rack and its pinion were separated during this cushioning action, due to the mutilated portion 49 of the rack, still the pinion and the rack teeth were at all times in the same horizontal plane and upon the feed pinion contacting with the first tooth to the right of the mutilated portion (see Fig. 1) the pinion of course will immediately engage that tooth which positively and finally arrests the head against further movement in letterfeed direction, until of course the type key or space bar be operated. Therefore, when the usual hand tripping lever 16 be operated, the electrical circuit will be closed and the head through the clutch mechanism, belt 44 and spring 45, will be caused to move in contra-letterfeed direction until it is gradually arrested by the plunger 50 and then returned in the opposite direction by the usual carriage motor mechanism and finally arrested at the exact initial writing point. The operator, of course, holds the hand tripping lever depressed during this movement and until the head comes to final rest. 53 indicates a dash pot mechanism of similar construction to the mechanism already described. The plunger of the mechanism 53 is secured to the rolling frame and is adapted to contact with a block 54 secured to the member 3 which of course is a part of the fixed typewriter stand. If the writing upon any given sheet be completed, requiring no further line spacing it is of course necessary to cause the head to move rearwardly so as to allow the removal of the written sheet. Therefore, the usual hand tripping lever 16 is not operated, because it would not only close the electrical circuit but would hold the head from longitudinal movement towards the bar 3, and on the contrary would cause the head to move longitudinally in the opposite direction towards the operator, if it were not for the pull of the motor. The operator therefore now depresses the lever 55 instead of the usual hand tripping lever 16 which will of course cause the head to move laterally with respect to both the rolling frame or platen and at the same time to retreat longitudinally of its bed and away from the operator. The head being now free to move both laterally and longitudinally will take a diagonal path until it finally comes to rest adjacent the motor, having been returned meanwhile to its initial writing position and the rolling frame having likewise been fully returned so as to uncover the writing

bed or platen, and allow the removal of the written sheet. When the rolling frame moved longitudinally as just described, it was arrested by the dash pot mechanism 53 contacting with the block 54 so that the arrest was fully cushioned in the same manner as was the arrest of the head.

I claim:

1. A typewriting machine having a writing bed and a head adapted for movement transverse the bed and also in a direction opposite to normal line spacing, and a means to apply power for imparting both such movements simultaneously.

2. A typewriting machine having a writing bed and a head adapted for movement transverse the bed and also in a direction opposite to normal line spacing, and a means for imparting both such movements, and mechanism for independently controlling said means to cause it to impart such movements simultaneously or separately at will.

3. A typewriting machine having a writing bed and a head adapted for transverse movement and for longitudinal movement opposite to normal line spacing movement, a motor connected to operate the head for both such movements and selective controls for the motor, in the use of one of which the head will be subjected to both such movements simultaneously and in the use of another of such controls the head will be subjected to but one of such movements.

4. A typewriting machine having a writing bed and a head adapted for movement transverse the bed and for movement longitudinally thereof in opposition to the normal line spacing movement, a motor connected with the head for operating said head in such movements, means carried by the head for limiting the motor operated movement of the head to the transverse movement, and means carried by the machine for causing the motor operated movement of the head to be both transverse and longitudinal.

5. A typewriting machine having a flat writing bed and a head adapted for transverse movement of the bed and for longitudinal movement in opposition to the normal line spacing movement, power means connected to the head and capable of imparting both such movements to the head, and selective means for preventing longitudinal movement of the head under the power of the motor.

6. A typewriting machine having a flat writing bed and a head adapted for transverse movement of the bed and for longitudinal movement in opposition to the normal line spacing movement, power means connected to the head and capable of imparting both such movements to the head, and selective means for preventing longitudinal movement of the head under the power of the motor, while permitting the motor operated transverse movement of the head.

7. A typewriting machine, motor means for operating the carriage thereof in a letter-feed direction, means for operating the carriage against said motor means, and means for insuring the final arrest of the carriage at its initial writing point, said means including a disconnection of the typewriter feed mechanism without independent operation of any of the parts of such mechanism.

8. A typewriting machine having a motor mechanism for moving the carriage in a letter-feed direction, means for operating the carriage against the motor means, a banking stop to limit movement of the carriage under such means and means to disconnect the feed rack and opening

of the carriage as the carriage approaches the banking stop without independent movement of the feed rack.

9. In a typewriting machine having a writing bed and a head adapted for movement transverse to the bed for longitudinal movement for line spacing and for longitudinal movement in opposition to line spacing, of a motor for imparting said transverse movement and said longitudinal movement in opposition to line spacing, a manually operable member for operating the head for line spacing movement and simultaneously energizing the motor for transverse movement of the head, and a second manually operable member for energizing the motor for simultaneously moving the head transversely and longitudinally in opposition to line spacing.

10. A typewriting machine including a fixed frame, a rolling frame longitudinally movable thereon, a typewriter head transversely movable on the rolling frame and a motor operable to move the head on the rolling frame, and to move the head and rolling frame longitudinally on the fixed frame in opposition to the line spacing movement of said rolling frame, a manually operable member carried by the rolling frame and adapted to impart a movement to said frame in line spacing direction and simultaneously induce a motor operation of the head transversely of the rolling frame, and a member carried by the fixed frame of the machine to cause the motor to simultaneously move the head transversely of the rolling frame and to move the rolling frame and head longitudinally of the fixed frame in opposition to the line spacing movement of the rolling frame.

11. A typewriting machine including a fixed frame, a rolling frame longitudinally movable thereon, a typewriter head transversely movable on the rolling frame and a motor operable to move the head on the rolling frame and to move the head and working frame longitudinally on the fixed frame in opposition to the line spacing

movement of said rolling frame, a manually operable member carried by the rolling frame and adapted to impart movement to said frame in line spacing direction and simultaneously induce a motor operation of the head transversely of the 80 rolling frame, and a member carried by the fixed frame of the machine to cause the motor to simultaneously move the head transversely of the rolling frame and to move the rolling frame and head longitudinally of the fixed frame in opposition to the line spacing movement of the rolling frame, said first mentioned manually operable member rocking the rolling frame against longitudinal movement in opposition to the line spacing movement.

12. The combination with a typewriting machine, including a movable carriage and motor mechanism therefor, carriage feeding mechanism and a banking stop, of means which insures the final arrest of the carriage at its initial writing 95 point, said means including means for disconnecting the carriage feed mechanism without taking any part of said mechanism out of its normal horizontal plane.

13. The combination with a typewriting machine, of a motor for moving the carriage in contra-letterfeed direction, a flexible connection between the motor and the carriage and an elastic banking stop and means for insuring the final arrest of the carriage at its initial writing point 105 after the carriage has been temporarily arrested by its elastic banking stop, said means permitting its free and uninterrupted return movement to the initial writing point after such temporary arrest by the elastic stop.

14. In a machine of the class described, a platen, a carriage movable both longitudinally and transversely thereof, and means for moving the carriage in both directions, including a single connecting member extending between the motor 115 and carriage.
